UNITED STATES PATENT OFFICE.

ROBERT L. CAMPBELL, OF HAGERSTOWN, MARYLAND, ASSIGNOR TO HAGERSTOWN SHOE & LEGGING COMPANY, OF HAGERSTOWN, MARYLAND, A CORPORATION OF MARYLAND.

LEGGING.

1,097,582.

Specification of Letters Patent. Patented May 19, 1914.

Application filed April 24, 1913. Serial No. 763,409.

To all whom it may concern:

Be it known that I, ROBERT L. CAMPBELL, a citizen of the United States, residing at Hagerstown, in the county of Washington 5 and State of Maryland, have invented a certain new and useful Improvement in Leggings, of which the following is a full, clear, and exact description.

It is desirable to readily put on and take 10 off puttees and other leggings on which straps are used to adjust and fasten them. Fastenings that could be used as such without disturbing the adjustment of the straps, would seem to meet the requirements of 15 ready application and removal of the puttees or leggings; but any such fastenings in order to be entirely practical as well from a manufacturing viewpoint as from that of the user, must be simple and devoid of complications, 20 and also efficient.

The object of this invention is to supply such fastenings.

The invention consists of a legging having a chafe, or combined adjusting and fastening member, supplied with means by 25 which the free ends of the straps may be adjustably secured, and means for connecting the chafe with the body of the legging in such way that it may be readily fastened and 30 unfastened to apply the legging to the wearer's leg and as easily remove it, without altering the adjustment of the straps on the chafe, as I will proceed now to explain and finally claim.

35 In the accompanying drawings illustrating the invention, in the several figures of which like parts are similarly designated, Figure 1 is an elevation of a legging or puttee having an upper and a lower strap adjusted in a single chafe and the fastening means. Fig. 2 is a plan view of the chafe and fastening shown in Fig. 1, and Fig. 3 is a longitudinal section thereof. Fig. 4 is a plan view of a chafe which provides for adjustment of the fastening or connecting means, and Fig. 5 is a longitudinal section thereof.

50 The body 1 of the legging or puttee, may be of any suitable construction and material, and provided with any desired number of straps. Merely as illustrative of the principle of the invention, I have shown the body provided with a strap 2 at its upper or top portion, permanently fixed to one edge thereof, and a strap 3 at its lower or bottom por-

tion and similarly applied to the same edge. These two straps are adapted to be wound about the body of the legging when applied to the wearer, in order to bind the legging to the wearer's leg, and their free ends are adjustably secured to the chafe, here designated as a whole by the numeral 4. This chafe comprises a piece 5 of leather, metal, or other substance or material, having a part 6 to which the strap fastening and adjusting element 7 is secured, same being shown as an ordinary tongue buckle, although it may be of other suitable construction; and a connecting part 8 having a fastening element 9 to engage its complementary element 10 fixed to the body of the legging. As here shown, the element 9 is a hole in the part 8, and the element 10 is a hook, such as a shoe lacing hook. Such a chafe may be applied to each strap, but preferably the chafe will include as many strap fastening and adjusting elements 7 as there are straps, and I have herein shown it as supplied with two to take the two straps 2 and 3. In either case, the legging is tried on 80 and the straps adjusted in the buckles to the proper fit, and then the fastening or connecting elements 8-9 and 10 are used to fasten and release the legging. Obviously both operations may be performed quickly and 85 without altering the adjustment of the straps.

In order to extend the adjustability of the legging, and to compensate for any looseness or tightness of the fit, the chafe may be provided with a series of holes 9, Fig. 4; and instead of the hook 10, I may use a spring lever hook 11 of ordinary construction.

Any other suitable chafe fastener may be used, so long as it admits of the ready fastening and unfastening of the legging without altering the adjustment of the straps, or, in other words, unfastening the straps from the chafe.

In those leggings in which the straps are 100 threaded through eyes or loops so as to connect both edges, it is necessary to wholly remove the straps before the legging could be opened lengthwise in order to apply it to or remove it from one's leg by merely lapping 105 it and then fastening the straps, and hence such leggings are most expeditiously put on and off by drawing them over the feet. This is objectionable, particularly if the shoes happen to be wet or dirty. In my invention 110

the legging opens wide, with the straps wholly on one side, to put it on and off by movements transverse to the leg.

From the foregoing it will be apparent that the invention provides what may be appropriately termed a quick-acting fastener.

What I claim is:—

1. A legging, having top and bottom straps, a chafe for connecting said straps for conjoint operation, comprising a body having an individual strap-engaging and adjusting element for each of said straps, and a holed part, and a hook on the legging adapted to coöperate with the said holed part to fasten and unfasten the straps quickly and without disturbing their connection with the said chafe, and to permit

the legging to be opened wide for putting it on and off.

2. A legging, having top and bottom straps, a quick-acting chafe having strap-engaging and adjusting buckles and also having a legging-engaging part provided with a series of holes, and a hook on the legging to be engaged by any one of such holes to adjust and fasten the legging about the wearer.

In testimony whereof I have hereunto set my hand this 21st day of April A. D. 1913.

ROBERT L. CAMPBELL.
